Martin T. Fisher,

Atty.

UNITED STATES PATENT OFFICE.

PERCIVAL MOTT, OF NORTON, MASSACHUSETTS.

ADJUSTABLE SHELF.

Application filed November 17, 1923. Serial No. 675,272.

To all whom it may concern:

Be it known that I, PERCIVAL MOTT, a citizen of the United States, residing in Norton, in the county of Bristol and State of Massachusetts, have invented certain new and useful Improvements in Adjustable Shelves, for which the following is a full and complete specification, reference being had to the accompanying drawings.

10 This invention is an adjustable shelf, particularly designed for use in a window, the shelf being adjustable in length so that it will fit windows of various sizes.

One of the important features of the improved shelf is that it locks itself in place in the window without the use of screws, bolts, nails or similar attaching devices that would tend to disfigure the woodwork around a window. Furthermore, this locking of the 20 shelf is effected by gravity, that is, by the weight of the shelf itself. The shelf is simply placed in position, and stays there, by reason of the engagement of the supporting elements of the shelf with vertical and horizontal portions of the window.

A second important feature of the shelf is that it comprises only two movable parts, these parts being the two telescoping parts of the shelf ledge; a supporting bracket is 30 fixed to each end of these telescoping sections.

Another improved feature of the shelf is that the brackets support the top surface of the ledge of the shelf flush with the top horizontal surface of the top of the window sash, so that the one supplements the other and gives a supporting surface as wide as the combined widths of the two.

Still another improved feature of the shelf 40 is that when it is once adjusted in length for a particular window, it may be removed from the window, and put back in the window, without further varying its length.

The invention also resides in improved 45 structural details that will be explained by reference to the accompanying drawing, illustrating a preferred embodiment of the invention.

In this drawing:

50 Figure 1 is a perspective view, showing the shelf in two positions in a window;

Fig. 2 is a front elevation of the shelf;

Fig. 3 is a plan;

Fig. 4 is an enlarged section, taken on the line 4—4 of Fig. 1;

55

Fig. 5 is an end view of one of the supporting brackets;

Fig. 6 is an end view of one of the telescoping sections with the bracket removed;

Fig. 7 is a section on line 7—7 of Fig. 4, 60 but with the bracket in position; and

Fig. 8 is a view of a detail.

Referring now to these figures, in which similar reference characters indicate similar parts and in which all of the parts of the shelf are preferably metal, such as brass, the ledge or bottom portion of the shelf consists of two telescoping sections 1 and 2; the longitudinal edges of each section are bent down and then up to form vertically disposed telescoping flanges 3, which serve to strengthen and stiffen the shelf very materially.

A box-like end is formed on the end of each of the sections 1 and 2 by bending inwardly a pair of flaps 5, and then folding 75 downwardly thereover a tongue 6, the metal being suitably slotted to define such flaps and tongue. This box end with its several layers of metal—here shown at five—gives strength to the shelf at a vital point, for it is at this point that the supporting brackets 7 are attached to the shelf.

A supporting bracket 7 comprises a vertical plate the lower portion of which is secured to a box end of a telescoping ledge 80 portion 1 or 2, by securing devices 8.

At the upper, rear part of the supporting bracket is an outwardly extending gripping lug 9 provided with a vertical bearing face 10 facing toward the front of the shelf. 90 This lug is adapted to engage behind one of the vertical elements 11 of a window frame, and to resist an outward or lateral pull.

At the lower, rear portion of the bracket are provided bearing surfaces 12 and 13 respectively, formed by cutting a notch 14 in the bracket; surface 12 supports most of the weight of the shelf, and is at a level so as to support the top of the shelf flush with the top of the horizontal sash 15 of the 100 window, whereby the two top surfaces supplement each other and give a supporting surface equal to the combined width of the two, as shown in Fig. 4. Surface 13 bears 105 against the front of the sash 15.

As shown in Figs. 1, 2 and 7, each of

the brackets 7 is provided with a horizontally and transversely extending rib 20, which stiffens the bracket and covers the joint where the bracket and its corresponding telescopic section meet.

In operation, the shelf holds itself in place entirely by gravity; the notch 14 is placed over the corner of the sash 15; the shelf is extended until the lugs 9 engage 10 behind the vertical elements 11 of the window, and the shelf is ready for use. The shelf may be removed, by shortening it and thus disengaging lugs 9, or by lifting one end through an arc, as in Fig. 2, thus disengaging lugs 9; it may be put in place by reversing these operations.

In order to use the shelf on a window sill, which is considerably wider than a sash, supplementary plates 25 may be used, and 20 are attached to the window frame to provide engagement for the gripping lugs 9. Each of these plates is provided with an aperture 26 for the reception of a lug 9, and with a screw hole 27 for reception of 25 an attaching screw 28. In operation notch 14 engages over the edge of the window sill 29 (see the lower part of Fig. 1) and lugs 9 engage in holes 26.

While the preferred material for the shelf 30 is metal, such as brass, aluminum or steel, other materials might be used. Furthermore, it should be understood that this disclosure of a preferred embodiment of the invention is illustrative only, and that the 35 inventive idea involved may be carried out in other ways than by the exact structural details shown and described.

I claim as my invention:

1. A window shelf comprising telescoping ledge portions, an end bracket fixed to 40 the outer end of each ledge portion, the brackets being movable back and forth with the ledge portions as they telescope, a notch at the lower inner end of each bracket for engaging over a horizontally extending edge portion of a window, and an outwardly extending lug at the upper end of each bracket for engaging behind a vertical element of a window frame, whereby a shelf 45 comprising only two parts is formed, which is adjustable to fit different sized windows, which is locked in place by gravity, and which may be removed by simply lifting it from the window.

2. An adjustable shelf comprising flanged telescoping ledge portions formed with box-like ends, end brackets, each having a flat inner side, which flat side is secured against 55 a box-like end of the ledge portion, each bracket being movable back and forth with

its ledge as it telescopes, a lug carried by the outer side of each bracket for engaging behind a vertical element of a window frame, and a notch at the lower, inner end of each bracket for seating on a horizontally 65 extending portion of a window.

3. An adjustable shelf comprising substantially flat telescoping members provided with downwardly extending telescoping flanges, whereby to form a flat ledge portion with stiffening ribs extending lengthwise thereof and extending downwardly therefrom, a bracket secured to the outer end of each telescoping member and movable back and forth with it, and means carried by the bracket for engaging with horizontal and vertical parts of a window frame, whereby the shelf will fit windows of various sizes, will lock in place therein by 70 gravity and may be removed from the window by simply lifting it.

4. In combination, a window shelf comprising two telescoping ledge portions, an end bracket fixed to the outer end of each ledge portion and movable back and forth with it, a notch and a lug formed at the lower and upper parts, respectively, of each bracket, and plates, normally permanently secured to the window frame, provided with means for detachably engaging with the 80 lugs on the upper parts of the brackets, whereby the shelf may be locked in place by gravity by engaging said notch over a horizontally extending portion of a window frame, and by engaging the lugs with 85 said plates, and may be removed by lifting on the shelf without disturbing the plates.

5. An adjustable window shelf comprising in combination substantially flat telescoping members provided with downwardly extending telescoping flanges, whereby there is formed a ledge the upper surface of which is flat, while the telescoping flanges act as stiffening ribs, and a bracket secured to the end of each of the telescoping members and extending well above the top surface of the ledge, said brackets serving to keep articles from falling off the end of the shelf, each bracket having a notch at its inner, lower part for engaging over a horizontally extending edge of a window frame and also having a lug extending outwardly therefrom, for engaging behind a vertical element of a window frame, whereby the shelf may be locked in place in a 100 window by gravity.

In testimony whereof, I have hereunto affixed my signature.

PERCIVAL MOTT.
